ATTORNEY.

UNITED STATES PATENT OFFICE.

JOHN H. STEWART, OF CINCINNATI, OHIO.

CONTROL SYSTEM FOR FUEL BURNERS.

Application filed April 20, 1926. Serial No. 103,350.

My invention relates to fuel burner control systems which incorporate in automatic controlling devices the operation of a fuel burner ignition system, the power element 5 with which the burner is operated, and the means of supplying the burner with fuel.

It is my object to provide an electric circuit in a control system which will effect automatic operation of the burner and 10 which also will provide exceptional safety to the system against excessive flow of oil in case of non-ignition, and which will prevent wasteful use of electric current in case the storage tank is exhausted of oil. It is also 15 my object to provide a circuit which will break the circuit of the power line upon failure of the automatic controlling devices to function properly.

It is the object of my invention to provide 20 electrical controlling means particularly for an oil burning system which is composed of a burner operated by an electric motor, an igniter with which the fuel is ignited and a pump with which fuel is supplied to a 25 gravity flow reservoir.

Incorporated in my control system in combination with an air current supply means for a fuel burner such as is described in my co-pending application, Serial No. 93- 30 008, filed the 8th of March, 1926, it is my object to provide a novel quick acting thermostat, actuated by the heat of the burner, which will automatically inhibit the ignition means after the fuel is ignited and 35 incidentally prohibit the opening of a master or time limit switch, thus maintaining the burner in operative condition.

Further incorporated in my controlling system is a novel master or time switch, the 40 object of which is the inhibition of the electric power after a certain interval. It is my object to utilize the time switch for the primary control of the entire system and to so connect the time switch element which 45 controls the system that upon failure of the burner to light properly the entire system is inhibited, but with the successful lighting of the burner the system becomes automatically regulating, being controlled 50 by the usual room thermostat or the auxiliary boiler control in case the system is for a hot water, or steam heating plant.

It is my object to provide a control system 55 which will operate automatically without the necessity for a pilot light, so that when no heat is required there is no waste of fuel.

The above and other objects which will be noted in the ensuing description, are incorporated in a controlling system which I have illustrated in its preferred embodiment. 60

Referring to the drawings:

Figure 1 is a diagrammatic elevation of the system including the preferred wiring arrangement.

Figure 2 is a horizontal section of the thermostatic ignition control box. 65

Generally indicated in the diagrammatical elevation in Figure 1. I have shown the fuel burner 1 preferably disposed on the shaft of a motor 2. An igniter 3 is shown, 70 the preferred type illustrated being a carbon arc lighter as described in my co-pending application Serial No. 94,080, filed March 11th, 1926. Current which is supplied from the power feed lines 4 passes first through 75 the main control box assembly indicated at 5 and then through the thermostatically controlled ignition control box 6. The pump 7 which provides a supply of fuel for the burner is preferably of the type described 80 in my co-pending application Serial No. 97,106, filed March 24, 1926, comprising a gravity reservoir with which oil is supplied to the burner and an automatically controlled pump which keeps the reservoir filled 85 as long as a supply is required for the burner and then shuts off when the supply is no longer required.

Incorporated in the main control box 5 I have shown a preferred type of time switch 90 indicated at 8 which cuts off the current to the entire system if the burner fails to light within a certain time. The power feed line indicated at the left in Figure 1 will be traced first. It is preferably connected with 95 a room thermostat 9 and a boiler control element 10 in accordance with usual boiler room and furnace installation practice. The room thermostat and boiler control, however, are optional and depend on the requirements of the heating system. From the contact post 11 in the main control box, if the thermostat and boiler control are incorporated in the system a line 12 connects with the one of the terminals 13 of the room 100 thermostat, the line 14 passing to the thermostat and returning to the other terminal 15 from which the line 16 connects with one of the terminals 17 of the line 18 which leads to the boiler control element. The return 105 from the boiler control element may be suitably connected to a terminal 19 from which 110

electrical current is distributed to the system. The room thermostat and the boiler control function in the usual way, the room thermostat breaking the circuit when the temperature rises above a certain temperature and the boiler control breaking the circuit when the boiler pressure rises above a certain pressure. As noted these controls form no part of my invention and the structure of the several controlling elements may be of any desired type.

To the terminal 19, one line indicated at 20 is connected, which leads to the input end 8 of a time switch. The preferred structure of the time switch is as indicated with a spring arm 24 mounted on a bracket 25 electrically connected with the input line 20. The spring arm is held in connected position by a bimetallic element 26 which is mounted on a bracket 27, which is electrically connected with the output line 28 which leads to the system. A resistance element 29 is mounted in proximity to the element 26 forming a series connection between the input and output lines of the switch. After a certain interval the resistance element heats the bimetallic element so that it moves toward the heating element and releases the spring arm 24 which springs toward the position shown in dotted lines and breaks the circuit at the position indicated at 30. I also provide a hand operated plunger 31 which sets the time switch back to connected position. From the output end of the time switch the line 28 leads to a terminal connection 32. From the terminal connection 58 a line leads to one of the terminals 33 from which a line 34 is extended to the automatic regulating pump 7. The other feed line of the pump indicated at 35 is connected with the terminal 36 which is connected with the other power feed line indicated at the right in Figure 1 which is preferably on the grounded side of the power feed line. The pump operation is fully described in my co-pending application hereinbefore referred to so that no further mention need be made of its method of operation, excepting that my electrical control system includes the control of the pumping element with which fuel is supplied to the burner. As I have provided for another control of the fuel supply incorporated in my pump assembly, by including the pump in my system, I have provided a double means of positively inhibiting a supply of fuel to the burner which is an added insurance against flooding the boiler or furnace room floor with fuel and creating an additional fire hazard.

The line 22 from the terminal 58 leads to the right hand terminal 23 in the thermostatic ignition control box 6. This box is enclosed in a casing 39 having an air supply pipe 40 which during the operation of the burner is supplied with air from the same

source as the burner. The casing has an end 41 which is mounted in close proximity to the furnace fire box so that a bimetallic spiral 42 mounted on a shaft 43 will, with the coiling and uncoiling of the bimetallic element 42 tilt a mercury tube 44 which is carried by the shaft 43 in a clockwise or counter clockwise direction, depending on whether the furnace is heating up or cooling off. In order to protect the tube 44 from tilting too far in either direction, stops as indicated at 59 are provided which abut a pin 60 at the limit of counter and clockwise tilting.

When the bimetallic element is not subjected to heat the mercury tube will be tilted in a counter clockwise direction with the left hand portion of the stop 59 bearing against the pin 60 which allows the current to pass through a line 44^a to the igniter. If the furnace lights up satisfactorily, the tube is then tilted in a clockwise direction by the bimetallic element 42 and a connection is established which is in shunt with the resistance coil 29 of the time limit switch and this prevents the time switch from tripping and breaking the circuit. For increasing the rapidity with which the thermostatic control operates an air conduit 40 is disposed in the casing 39 which directs a current of air against a flapper valve 45, thus cutting off the flow of induced air to the bimetallic spiral element 42 so that there will be a quicker rise in temperature from the oil flame due to the absence of the induced air. Also when the burner motor stops, the flapper valve opens by gravity allowing induced air to reach the spiral bimetallic element 42 and cause a quicker reduction in temperature after the oil flame has gone out.

The connections with the motor 2 are through a line 46 which extends from the right hand terminal 23 to the terminal 47 from which the line 48 extends to the motor, and through the line 49 from the motor to a terminal 50 which is connected to a ground 51. I have further provided a line 52 extending from the terminal 50 which is connected with a line 53 which leads back to the main control box 5 in which it is connected with a terminal 34 which has a line connecting it with the terminal 36.

The motor connecting lines have shunt lines 55 which lead to a cut-off valve 56 preferably of the solenoid type which inhibits the flow of oil to the burner unless the motor is operating. From the terminal 32 in the main control box a line 57 is connected with the centrally disposed terminal 38 which supplies the current for the ignition with the mercury tube tilted in a counter clockwise position.

The operation of the system is as follows: Starting the system with the time switch unset the only necessary manual adjustment

- is the pushing in of the spring arm 24 to locked position with the end of the bimetallic element 26. Then the current is supplied both to the pump 7 and through the line 57 to the central terminal in the box 6. As the mercury tube will be tilted to the left current will pass through the line 44^a to the carbon lighter. Under normal conditions the line 46 will also provide current for operating the motor 2 and the burner will ignite. As soon as the burner is lighted the mercury tube is tilted to the right, which shuts off the igniter. Should the igniter light and the fuel fail to light the time switch will, after the required interval, break the entire circuit so that everything will be shut off. It then becomes necessary for the operator to examine the system to discover what is wrong and before the system can be started up the plunger 31 must again be pushed in to set the time switch. If during the operation of the motor, due to some such cause as insufficient draft, the fire is smothered and goes out the mercury tube will be tilted to the left. This will allow the continued operation of the burner with the lighter on until the burner is again lighted or until the time switch again cuts off the entire system.
- 30 Modifications in structure will readily occur to those skilled in the art, but in so far as these changes amount to no more than the substitution of well known equivalents for those devices which I employ which are well known in the art I consider such changes within the scope of my invention.
- Having thus described my invention what I claim as new and desire to secure by Letters Patent is:
- 40 1. In combination with an electrical control system for an automatic fuel burner, a thermostatic switch comprising a housing, a bimetallic element, a shaft, a mercury tube and a flapper valve mounted within the housing adapted to close off the flow of induced air over the bimetallic element during periods of burner operation, and adapted to open by gravity, thus admitting induced air to the bimetallic element when the burner fails to properly ignite.
2. In combination with a fuel burning system, and an electrical system for controlling the operation thereof, a thermostatic element adapted to control the operation of said electrical system, and means 55 actuatable by air currents for accentuating the operation of said thermostatic element, said means comprising an air conduit with an open end directed toward said thermostatic element, and a member adapted to 60 inhibit the passage of air through said conduit during periods of fuel burning operation.
3. In combination with a fuel burning system, and an electrical system for controlling the operation thereof, a thermostatic element adapted to control the operation of said electrical system, and means of accentuating the operation of said thermostatic element, said means comprising an air 65 conduit with an open end directed toward said thermostatic element, and a member adapted to inhibit the passage of air through said conduit during periods of fuel burning operation, said member being so supported 70 with relation to said air conduit as to drop by gravity out of inhibiting position during periods of cessation of fuel burning operation.
4. In combination with a fuel burning system, and an electrical system for controlling the operation thereof, a thermostatic element against which cooling air currents may be directed, adapted to control the operation of said electrical system, and 75 means actuatable by air currents for controlling the flow of cooling air currents against said thermostatic element.
5. In combination with a mercury switch for controlling an automatic fuel burning system, a spiral bimetallic element against which cooling air currents may be directed, having a fixed end, a shaft extending axially of the spiral element and connected with its movable end, and said mercury switch 90 mounted on said shaft, and air pressure controlled means for controlling the flow of cooling air currents against the bimetallic element.
